UNITED STATES PATENT OFFICE.

AUGUST E. SCHULTZ, OF FOREST PARK, ILLINOIS, ASSIGNOR OF ONE-HALF TO
ARTHUR A. JAHR, OF FOREST PARK, ILLINOIS.

RAILWAY BUMPING POST.

Application filed October 7, 1926. Serial No. 140,086.

My invention relates to railway bumping posts employing base rails and other rails, usually sloping, uniting the bumping blocks with the base rails, the invention having for its object the provision of means for assembling the rails without materially altering the structure thereof.

My invention is of particular service in connection with those bumping posts in which the base rails are continuations of the track rails upon which the railway vehicles travel and the sloping rails are sections of similar track rails shaped to adapt them to their purpose. By means of my invention no assembling bolts need be passed through the webs of the rails that are included in the formation of the post nor need the flanges of the rails be modified in construction, these being features of advantage in the construction and maintenance of such a post, the cost of construction being reduced and the strength thereof being increased.

In the preferred embodiment of my invention, the lower ends of the sloping bumping block supporting rails are assembled, at their lower ends, with the base rails by clamps, there being two adjustable clamping jaws between the lower end of each sloping rail and the adjacent base rail. There are other jaws complementary to the aforesaid jaws, these additional jaws being held in suitably fixed position preferably by being formed in one integral casting with a yoke that joins them and which embraces the corresponding rails. This yoke desirably underlies the rails. There is such a structure at the lower end of each sloping bumping block carrying rail and as there are desirably four such inclined rails, there are four clamping mechanisms, two in association with each base rail and respectively abreast of the other two. Transverse tie rods connect each two yokes that are abreast to prevent the base rails of the post and the lower ends of the bumping block supporting rails from spreading apart.

I will explain my invention more fully by reference to the accompanying drawing in which Fig. 1 is a side elevation of the preferred embodiment thereof; Fig. 2 is a plan view; Fig. 3 is a plan view, on a larger scale, showing one of the clamps and portions of the rails clamped together thereby, one of these rails being shown partially in sec-

tion; and Fig. 4 is a sectional view on line 55 4—4 of Fig. 3.

The bumping block 1 is of any suitable construction, the bumping block illustrated having a rearwardly extending continuation 1' which is clamped between the upper ends 60 of rear rails 2 and 3 that slope and converge forwardly and upwardly. These rails 2 and 3 are clamped between the upper ends of the front rearwardly and upwardly sloping and converging rails 4 and 5 by means 65 of the clamping bolts 6. It is obvious that other construction may be employed for effecting the assembly of the bumping block with the rails 2, 3, 4 and 5. The lower ends 2', 3', 4', 5' of the rails 2, 3, 4 and 5 are 70 deflected to extend horizontally and in close parallel directions, these rail ends being in the same horizontal plane and being disposed between the base rails 7 and 8 of the post. Just sufficient space preferably intervenes between the adjacent rail ends 2', 3', 75 4' and 5' and the adjacent base rails for the reception of clamping bolts 9 between them. All of the rails that enter into the post structure are desirably railroad track 80 rails having the usual rail heads, webs and flanges as shown most clearly in Fig. 4, the base rails being desirably continuations of the track upon which railway vehicles run.

Each clamp is desirably inclusive of two 85 adjustable clamping jaws or blocks 10, which are received between the flange of the adjacent base rail and the flange of the horizontal lower end of the adjacent inclined rail. The inner faces of each pair of adjustable clamping blocks 10 desirably slope downwardly and inwardly so as to converge. The wedging block 11 of each clamp is interposed between the two adjacent adjustable flange and web clamping blocks 10 and 90 is drawn downwardly upon by one or more bolts 9, whereby these clamping blocks are spread apart to the extent limited by the two rail webs between which they are disposed, these rail webs, in turn, being held 95 100 from spreading apart by a pair of stationary clamping jaws 12 and 13, which are desirably integral parts of a casting which includes a rigid yoke 14 that embraces and desirably underlies the rails located between 105 the latter jaws. The bolts 9 pertaining to each clamp desirably pass downwardly through the yoke of such clamp and between

the adjacent rail flanges. The heads of these bolts are desirably received in the wedging blocks 11, these bolt heads and said wedging blocks being desirably below the heads of the adjacent rails. The bolts 9 are threaded at their lower ends to receive the clamping nuts 15, which are screwed upon the bolts and against the bottoms of the yokes 14 to draw the heads of said bolts downwardly to press the wedging block 11 downwardly sufficiently to very rigidly assemble the adjacent base and inclined rails of the post together by clamping the blocks 10 against the flanges and webs of the rails. The ends of the clamping blocks 10 are desirably inwardly extended as indicated at 10' in Fig. 3, so as to afford shoulders which will prevent creepage of the blocks.

The rods 16, extend crosswise of the track and through the portions of the opposite yokes 14, each tie rod 16 serving to rigidly assemble each pair of clamping devices that are located abreast to prevent the rails from spreading. The yokes 14 are desirably provided with strengthening flanges 14' which serves to prevent the yokes from buckling and otherwise impart rigidity thereto.

Changes may be made without departing from the invention.

Having thus described my invention, I claim:

1. A railway bumping post including horizontal base rails each having a head, web and flange; four rails between the base rails and also having heads, webs and flanges, two of these rails sloping and converging upwardly in a forward direction and the remaining two of these rails sloping and converging upwardly in a rearward direction; a bumping block carried by the upper ends of the four sloping rails, the lower ends of these sloping rails being horizontally continued along the aforesaid base rails, one of these base rails having the lower end of one of the forwardly sloping rails and the lower end of one of the rearwardly sloping rails in proximity thereto, the lower ends of the remaining sloping rails being in proximity to the other base rail; and four clamping structures, the lower end of each sloping rail being supplied with a clamping structure for assembling it with the adjacent base rail, each clamping structure comprising a pair of jaws engaging the outer sides of the webs of the rails to which it pertains, a yoke connecting these jaws and embracing these rails, two clamping blocks disposed between these rails and respectively engaging the inner sides of their webs and having their opposed faces converging, a wedging block interposed between said clamping blocks, and a clamping bolt structure assembling said wedging block and yoke and forcing the wedging block into wedging engagement with the aforesaid clamping blocks.

2. A railway bumping post including horizontal base rails; four rails between the base rails, two of these rails sloping and converging upwardly in a forward direction and the remaining two of these rails sloping and converging upwardly in a rearward direction; a bumping block carried by the upper ends of the four sloping rails, the lower ends of these sloping rails being horizontally continued along the aforesaid base rails, one of these base rails having the lower end of one of the forwardly sloping rails and the lower end of one of the rearwardly sloping rails in proximity thereto, the lower ends of the remaining sloping rails being in proximity to the other base rail; and four clamping structures, the lower end of each sloping rail being supplied with a clamping structure for assembling it with the adjacent base rail, each clamping structure comprising a pair of jaws engaging the outer sides of the rails to which it pertains, a yoke connecting these jaws and embracing these rails, two clamping blocks disposed between these rails and having their opposed faces converging, a wedging block interposed between said clamping blocks, and a clamping bolt structure assembling said wedging block and yoke and forcing the wedging block into wedging engagement with the aforesaid clamping blocks.

3. A railway bumping post including horizontal base rails each having a head, web and flange; four rails between the base rails and also having heads, webs and flanges, two of these rails sloping and converging upwardly in a forward direction and the remaining two of these rails sloping and converging upwardly in a rearward direction; a bumping block carried by the upper ends of the four sloping rails, one of the base rails having the lower end of one of the forwardly sloping rails and the lower end of one of the rearwardly sloping rails in proximity thereto, the lower ends of the remaining sloping rails being in proximity to the other base rail; and four clamping structures, the lower end of each sloping rail being supplied with a clamping structure for assembling it with the adjacent base rail, each clamping structure comprising a pair of jaws engaging the outer sides of the webs of the rails to which it pertains, a yoke connecting these jaws and embracing these rails, two clamping blocks disposed between these rails and respectively engaging the inner sides of their webs and having their opposed faces converging, a wedging block interposed between said clamping blocks, and a clamping bolt structure assembling said wedging block and yoke and forcing the wedging block into wedging engagement with the aforesaid clamping blocks.

4. A railway bumping post including

horizontal base rails; four rails between the base rails, two of these rails sloping and converging upwardly in a forward direction and the remaining two of these rails sloping and converging upwardly in a rearward direction; a bumping block carried by the upper ends of the four sloping rails, one of the base rails having the lower end of one of the forwardly sloping rails and the lower end of one of the rearwardly sloping rails in proximity thereto, the lower ends of the remaining sloping rails being in proximity to the other base rail; four clamping structures, the lower end of each sloping rail being supplied with a clamping structure for assembling it with the adjacent base rail, each clamping structure comprising a pair of jaws engaging the outer sides of the rails to which it pertains, a yoke connecting these jaws and embracing these rails, two clamping blocks disposed between these rails and having their opposed faces converging, a wedging block interposed between said clamping blocks, and a clamping bolt structure assembling said wedging block and yoke and forcing the wedging block into wedging engagement with the aforesaid clamping blocks; and tie rods disposed transversely of the base rails, one tie rod assembling the yokes which pertain to the clamps that relate to the forwardly sloping rails and the other tie rod assembling the yokes which pertain to the clamps that relate to the rearwardly sloping rails.

5. A railway bumping post including horizontal base rails; four rails between the base rails, two of these rails sloping and converging upwardly in a forward direction and the remaining two of these rails sloping and converging upwardly in a rearward direction; a bumping block carried by the upper ends of the four sloping rails, one of the base rails having the lower end of one of the rearwardly sloping rails in proximity thereto, the lower ends of the remaining sloping rails being in proximity to the other base rail; and clamping structures, the lower end of each sloping rail being supplied with a clamping structure that serves to assemble it with the adjacent base rail, each clamping structure including rail clamping jaws.

6. A railway bumping post including horizontal base rails; four rails between the base rails, two of these rails sloping and converging upwardly in a rearward direction; a bumping block carried by the upper ends of the four sloping rails, one of the base rails having the lower end of one of the forwardly sloping rails and the lower end of one of the rearwardly sloping rails in proximity thereto, the lower ends of the remaining sloping rails being in proximity to the other base rail; and four clamping structures, the lower end of each sloping rail being supplied with a clamping structure for assembling it with the adjacent base rail, each clamping structure comprising a pair of jaws engaging the outer sides of the rails to which it pertains, a yoke connecting these jaws and embracing these rails, two clamping blocks disposed between these rails and having their opposed faces converging, a wedging block interposed between said clamping blocks, and a clamping bolt structure assembling said wedging block and yoke and forcing the wedging block into wedging engagement with the aforesaid clamping blocks.

7. A railway bumping post including horizontal base rails; four rails between the base rails, two of these rails sloping and converging upwardly in a forward direction and the remaining two of these rails sloping and converging upwardly in a rearward direction; a bumping block carried by the upper ends of the four sloping rails, the lower ends of these sloping rails being horizontally continued along the aforesaid base rails, one of these base rails having the lower end of one of the forwardly sloping rails and the lower end of one of the rearwardly sloping rails in proximity thereto, the lower ends of the remaining sloping rails being in proximity to the other base rail; and clamping structures, the lower end of each sloping rail being supplied with a clamping structure that serves to assemble it with the adjacent base rail, each clamping structure including rail clamping jaws.

8. A railway bumping post including horizontal base rails, each having a head, web and flange; four rails between the base rails and each also having a head, web and flange, two of these rails sloping and converging upwardly in a forward direction and the remaining two of these rails sloping and converging upwardly in a rearward direction; a bumping block carried by the upper ends of the four sloping rails, one of the base rails having the lower ends of one of the forwardly sloping rails and the lower end of one of the rearwardly sloping rails in proximity thereto, the lower ends of the remaining sloping rails being in proximity to the other base rail; four clamping structures, the lower end of each sloping rail being supplied with a clamping structure serving to assemble it with the adjacent base rail, each clamping structure including rail clamping jaws.

9. A railway bumping post including horizontal base rails; four rails between the

base rails, two of these rails sloping and converging upwardly in a forward direction and the remaining two of these rails sloping and converging upwardly in a rearward direction; a bumping block carried by the upper ends of the four sloping rails, one of the base rails having the lower end of one of the forwardly sloping rails and the lower end of one of the rearwardly sloping rails in proximity thereto, the lower ends of the remaining sloping rails being in proximity to the other base rail; four clamping structures, the lower end of each sloping rail being supplied with a clamping structure serving to assemble it with the adjacent base rail, each clamping structure including rail clamping jaws; and tie rods disposed transversely of the base rails, one tie rod assembling the clamping structures which pertain to the forwardly sloping rails and the other tie rod assembling the clamping structures which pertain to the rearwardly sloping rails.

10. A railway bumping post including horizontal base rails; four rails between the base rails, two of these rails sloping and converging upwardly in a forward direction and the remaining two of these rails sloping and converging upwardly in a rearward direction; a bumping block carried by the upper ends of the four sloping rails, one of the base rails having the lower end of one of the forwardly sloping rails and the lower end of one of the rearwardly sloping rails in proximity thereto, the lower ends of the remaining sloping rails being in proximity to the other base rail; and four clamping structures, the lower end of each sloping rail being supplied with a clamping structure serving to assemble it with the adjacent base rail, each clamping structure including rail clamping jaws.

11. A railway bumping post including horizontal base rails each having a head, web and flange; additional and upwardly extending rails each also having a head, web and flange; a bumping block carried by the upper ends of said additional rails, the lower ends of these additional rails being horizontally continued along the aforesaid base rails; and rail embracing clamping structures, the lower end of each of said additional rails being supplied with a clamping structure that serves to assemble it with the adjacent base rail, each clamping structure including rail clamping jaws.

12. A railway bumping post including horizontal base rails; additional and upwardly extending rails; a bumping block carried by the upper ends of said additional rails, the lower ends of these additional rails being horizontally continued along the aforesaid base rails; and rail embracing clamping structures, the lower end of each of said additional rails being sup-

plied with a clamping structure that serves to assemble it with the adjacent base rail, each clamping structure including rail clamping jaws.

13. A railway bumping post including 70 horizontal base rails, each having a head, web and flange; additional and upwardly extending rails and each also having a head, web and flange; a bumping block carried by the upper ends of said additional rails, the 75 base rails having the lower ends of said additional rails in proximity thereto; and rail embracing clamping structures, the lower end of each additional rail being supplied with a clamping structure serving to assemble 80 it with the adjacent base rail, each clamping structure including rail clamping jaws.

14. A railway bumping post including 85 horizontal base rails; additional and upwardly extending rails; a bumping block carried by the upper ends of said additional rails, the base rails having the lower ends of the aforesaid additional rails in proximity thereto; and rail embracing clamping structures, the lower end of each sloping rail being supplied with a clamping structure serving to assemble it with the adjacent base rail, each clamping structure including rail clamping jaws. 90

15. A railway bumping post including 95 horizontal base rails each having a head, web and flange; additional and upwardly extending rails each also having a head, web and flange; a bumping block carried by the 100 upper ends of said additional rails, the lower ends of these additional rails being horizontally continued along the aforesaid base rails; and rail embracing clamping structures, the lower end of each of said 105 additional rails being supplied with a clamping structure that serves to assemble it with the adjacent base rail, each clamping structure including rail flange clamping jaws. 110

16. A railway bumping post including 115 horizontal base rails, each having a head, web and flange; additional and upwardly extending rails and each also having a head, web and flange; a bumping block carried by the upper ends of said additional rails, the base rails having the lower ends of said additional rails in proximity thereto; and rail embracing clamping structures, the lower end of each additional rail being 120 supplied with a clamping structure serving to assemble it with the adjacent base rail, each clamping structure including rail flange clamping jaws.

17. A railway bumping post including 125 horizontal base rails each having a head, web and flange; additional and upwardly extending rails each also having a head, web and flange; a bumping block carried by the upper ends of said additional rails, the 130

lower ends of these additional rails being horizontally continued along the aforesaid base rails; and rail embracing clamping structures, the lower end of each of said 5 additional rails being supplied with a clamping structure that serves to assemble it with the adjacent base rail, each clamping structure comprising a pair of jaws engaging the outer sides of the webs of the 10 rails to which it pertains, a yoke connecting these jaws and embracing these rails, two clamping blocks disposed between these rails and respectively engaging the inner sides of their webs and having their opposed faces 15 converging, a wedging block interposed between said clamping blocks, and a clamping bolt structure assembling said wedging block and yoke and forcing the wedging block into wedging engagement with the aforesaid clamping blocks.

18. A railway bumping post including horizontal base rails each having a head, web and flange; additional and upwardly

extending rails each also having a head, web and flange; a bumping block carried by the upper ends of said additional rails; and rail 25 embracing clamping structures, the lower end of each of said additional rails being supplied with a clamping structure that serves to assemble it with the adjacent base rail, each clamping structure comprising a 30 pair of jaws engaging the outer sides of the webs of the rails to which it pertains, a yoke connecting these jaws and embracing these rails, two clamping blocks disposed between these rails and respectively engaging the 35 inner sides of their webs and having their opposed faces converging, a wedging block interposed between said clamping blocks, and a clamping bolt structure assembling 40 said wedging block and yoke and forcing the wedging block into wedging engagement with the aforesaid clamping blocks.

In witness whereof, I hereunto subscribe my name.

AUGUST E. SCHULTZ.
